CLAIM

The ornamental design for a spectrometer, as shown and described.

DESCRIPTION

1. Spectrometer
2. Spectrometer

For design 1: reproduction 1.1 is a perspective view of a spectrometer (probe cover closed); reproduction 1.2 is a front view of the spectrometer; reproduction 1.3 is a right view of the spectrometer; reproduction 1.4 is a left view of the spectrometer; reproduction 1.5 is a rear view of the spectrometer; reproduction 1.6 is a top view of the spectrometer; reproduction 1.7 is a bottom view of the spectrometer; reproduction 1.8 is a perspective view of a spectrometer (probe cover opened); for design 2: reproduction 2.1 is a perspective view of a spectrometer; reproduction 2.2 is a front view of the spectrometer; reproduction 2.3 is a right view of the spectrometer; reproduction 2.4 is a left view of the spectrometer; reproduction 2.5 is a rear view of the spectrometer; reproduction 2.6 is a top view of the spectrometer; reproduction 2.7 is a bottom view of the

(Continued)

spectrometer; with regard to all designs, the portions shown by means of broken lines in the reproductions are not part of the claimed designs.
